UNITED STATES PATENT OFFICE.

SETH A. WELLMAN, OF MASON CITY, IOWA.

MACHINE FOR TYING VALVE-SACKS.

1,229,361.

Specification of Letters Patent. Patented June 12, 1917.

Application filed June 18, 1916. Serial No. 104,502.

To all whom it may concern:

Be it known that I, SETH A. WELLMAN, a citizen of the United States, residing at Mason City, in the county of Cerro Gordo and State of Iowa, have invented a new and useful Machine for Tying Valve-Sacks, of which the following is a specification.

The object of the invention is to provide a machine for expeditiously and effectively 10 tying or closing the necks of valve sacks prior to the filling thereof, the tied sacks being furnished to the miller or dealer in that form, so that the filling of the sacks will constitute the completion of the packaging of the material; and a further object 15 is to provide an apparatus of this type wherein the consecutive operations are timed to insure accuracy and minimize the responsibility of the attendant.

Further objects of the invention will appear in the following description of a preferred embodiment of the invention, it being understood that changes in form, proportions, and minor details of construction 20 may be resorted to without departing from the spirit of the invention.

In the accompanying drawings:—

Figure 1 is a plan view of the machine.

Fig. 2 is a longitudinal sectional view, 30 partly in side elevation, of the machine.

Fig. 3 is a similar view taken from the opposite side of the machine, the same being partly broken away and showing the means for operating the carrier and the shuttle.

Fig. 4 is a vertical sectional view on the line 4—4 of Fig. 2 to show the mechanism for intermittently and reversibly operating the twister head.

Fig. 5 is a detail view of the shuttle and 40 twister head in the positions which they occupy as the tie wire is adapted to be engaged and cut.

Fig. 6 is a plan view of the parts illustrated in Fig. 5.

Fig. 7 is a plan view showing the same parts as in Figs. 5 and 6, with the shuttle arranged in the position which it occupies in delivering the end of the tie wire, prior to the twist, to the twister head.

Fig. 8 is a face view of the twister head.

The illustrated machine embodies essentially a carrier provided with sack holders 11 and adapted to be operated intermit-

tently or step by step to successively present the holders with the contained sack nets to 55 a twister mechanism 12 which is threaded by means of an intermittently movable oscillatory shuttle 13 which is provided with a cutter 14 to sever the tie wire 15 after the completion of a twist or tie, and, drawing 60 the same from the supply reel 16, to carry the end of said wire around the held neck of the sack 17 as illustrated in Fig. 7, and deliver the same to the twister head preparatory to a further operation of said 65 twister.

In the machine illustrated, the carrier is of the rotary type consisting of a table 18 to which is imparted intermittent motion from a main shaft 19 through a counter 70 shaft 20 geared to the main shaft, a spud shaft 21, in turn geared to the countershaft and carrying a tappet arm 22, a rocking lever 23 fulcrumed as at 24 to the supporting frame 25, and connected with a feed 75 pawl 26 which is adapted during its forward movement to engage notches or ratchet teeth 27 on a flange 28 depending from the table, said rocking lever being returned to its normal position by means of a 80 spring 29 after each active operation by means of the tappet arm 22.

The table of the carrier is provided with a series of sack holders 11 having outer jaws 31 pivotally mounted as at 32 upon 85 the table, and inner jaws 33 carried by stems 34 which are mounted in guides 35 and are provided at their inner end with means, consisting in the construction illustrated of rollers 36, for contact with a holder operating cam 37 which is stationary and around which the holders mounted upon the table travel. The stems 34 are pivotally connected at their outer extremities to the pivotal outer jaws 31 of the holders, as shown at 90 38, whereby as the stems receive reciprocal movement due to the engagement thereof by the cam 37, the jaws are mutually moved toward or from each other. In the construction illustrated, the guides 35 100 consist of sleeves secured to the upper surface of the table and are provided with slots 39, in which operate pins 40 projecting from the stems. Preferably the holders 11 remain closed during the greater portion 105 of the path of travel thereof and are opened

at or about the point A indicated in Fig. 1, so that the sacks are released or delivered at one point to facilitate the bundling thereof, while the filling of the holders or the engagement therewith of the neck of a sack to be tied, may take place at or about the point indicated by B in said figure. Also associated with the carrier 18, and in operative relation with the holders as they successively approach the same, there may be a tucker 41, shown in the drawings as of the star wheel type, supported by an arm 42 projecting from the frame 43 and adapted to offer sufficient resistance to the forward movement of the sack necks to insure the proper holding and compacting thereof in the opening between the jaws of the holders.

In order that the table 18 may be firmly held in position when at rest, and during the tying of the sacks, there may be employed a locking lever 44 pivotally mounted upon the frame 25 as at 45 and having a nose 46 for engagement with sockets 47 in a flange 48 depending from the table, said locking lever being connected with a slide 49 also mounted upon the frame 25 and having connected therewith an arm 50 which is arranged in the path of a tappet arm 51 carried by the counter shaft 20. The parts are so arranged that just prior to the engagement of the tappet 22 with the rocking lever 23 through which motion is communicated to the feed pawl 26, the locking device or latch 46 is tripped, to release the table, by means of the arm 51, and immediately the arm 50 is moved in the opposite direction by the spring 52, whereby the latch is held in readiness to engage the next succeeding notch or socket 47 to again lock the table against movement.

The sacks respectively engaged by the holders of the table are presented successively, and through the described intermittent or step-by-step movement of the table, to the tying mechanism which consists, in the construction illustrated, of telescoped outer and inner tubes 53 and 54 carrying respectively the disks 56 and 55 which constitute the twister head and are normally arranged in contact with their wire-engaging notches in registration. These engaging means consist of comparatively shallow guiding notches 57 and 58 formed respectively in the disks 55 and 56 and to which the tie wire is led from registering guide openings 59 and 60 in the tubular shafts 53 and 54 of the twister head, and relatively deep notches or slots 61 and 62, located, in the drawings, diametrically opposite the notches 57 and 58 and as hereinafter explained constituting clamping jaws for engagement with the free end of the tie wire as shown in Fig. 7, preliminary to the twisting operation.

Rotary motion is communicated to the exterior tubular shaft 53 through the agency

of a pinion 63 secured thereto and having in mesh a gear 64 carrying a pinion 65 with which engages a segmental rack 66 carried by a rocker arm 67, fulcrumed as at 68 upon the frame. The main or drive shaft 19 carries a cross head or tappet arm 69 for engagement alternately with tappets 70 and 71 secured to a slide 72 which in turn is connected with the lower arm of said rocking lever. An extension of the tappet arm 69 in the opposite direction from the drive shaft constitutes a limiting arm 73, which is arranged in the path of one tappet as the other is being actuated by the tappet arm, to prevent overthrow or excessive movement of the slide and hence of the segment 66. It will be noted that in the operation of the twister the heads by reason of the oscillatory movement of the rack 66, are alternately twisted in opposite directions, to avoid imparting a permanent twist in one direction to the tie wire which is led through the tubular twister head shafts from the tension roll 74 after leaving the reel or spool 16, said tie wire extending from the bore of the inner tubular shaft through the registering apertures or guide openings 60 and 59, as clearly illustrated in Figs. 6 and 7.

In operation the twister heads receive a definite number of revolutions for each operation, preferably three, and in order that the wire engaging means of the twister heads may be accurately and definitely registered at the end of each operation of the twister heads, the inner tubular shaft is provided with a weight 175.

The remaining essential feature of the apparatus consists of the shuttle designed to engage the free end of the tie wire as it protrudes from the guide openings 59 and 60 of the twister shafts and carry it through an orbital path around the projecting upper edge of the neck of a sack engaged by the presenting holder, and place it in the registering notches or slots 61 and 62 constituting the clamping jaws, and thereby forming a loop to be converted into a tie by the rotation of the twister head. The shuttle embodies an orbital arm 75 consisting of a crank shaft of which the upper, 76, of two parallel arms is mounted in a suitable bracket 77 and carries a pinion 78, while the lower, 79, of said parallel arms has mounted thereon the shuttle block 80, yieldingly held in a definite position, rotatably, with reference to the spindle 79, by means of a spring 81. This shuttle block is provided with wire-engaging jaws 82 and 83, of which the former, in the construction illustrated, is stationary with reference to the shuttle block 80, while the other is pivotally mounted thereon as at 84 and is provided with a tail 85 adapted to be actuated to close the jaws so as to grip the extremity of the tie wire. For convenience in operation and simplicity in con-

struction, the wire gripping jaws of the shuttle block also constitute a wire cutter, by providing a shear plate 86 with which the movable jaw of the gripper cooperates, thereby detaching from the body of the tie wire that portion which has been subjected to the operation of the twister, and which forms a part of the tie engaging the neck of the sack. The relations of the parts in operation 10 at this point will be clearly indicated by reference to Fig. 6. As the gripper is closed, the operations of severing the tie from the body of the wire and clamping the free end of the wire preparatory to carrying 15 the same around the neck of the succeeding sack, are accomplished simultaneously.

Oscillatory, or swinging movement alternately in opposite directions, is imparted to the orbital member of the shuttle by means 20 of a reciprocatory rack 86' which is permanently in mesh with the pinion 78, and receives motion from the crank disk 87 carried by the countershaft 20, said crank disk having a continuous rotary motion, and inasmuch as the shuttle block 80 is swiveled upon the spindle of the orbital member, the tension of the tie wire as it is drawn from the reel causes the said shuttle block to assume a position with the gripping jaws in line of 25 strain or resistance, against the tension of the spring 81 whereby the shuttle block is reversed in position so far as the direction of the jaws are concerned during the movement around the neck of the sack, whereby 30 when the shuttle reaches the position shown in Fig. 7 at the opposite side of the twister head, the block is reversed, and the tie wire, between the gripping jaws and the neck of the sack is passed into the slot constituting 35 the jaws of the twister head. Rotary motion now being applied to the exterior tubular shaft of the twister head causes the twister head jaws to grip the tie wire, because the turning movement of the inner tubular shaft 40 to which the counter weight 175 is attached, is resisted. This resistance brings the twister head jaws into firm engagement with the tie wire and this engagement remains until the rotation of the twister head has 45 been completed. As soon as the active twister head disk reaches its normal position, the counter weight brings the other twister head disk to its normal position, thereby opening the wire-engaging jaws of 50 the twister head and releasing the tie wire. As soon as the shuttle jaws are disengaged from the extremity of the tie wire, after placing the same in the jaws of the twister head, this release being accomplished by 55 means of a cam 88' engaging under and raising the tail 85 of the shuttle clamp, the shuttle block is free to turn under the influence of the spring 81 to restore it to its original position with reference to the 60 orbital arm. In order to accurately posi-

tion the shuttle block, in both of its locations at opposite sides of the twister head, so as to accurately engage the tie wire in the position shown in Fig. 6 and accurately deliver the wire to the twister head jaws as in Fig. 7, a limiting means is employed consisting in the construction illustrated, of a follower rod 88 operating at one end in a guide 89 on a stationary part of the machine as for example the cam 37, and pivotally connected 70 at its other end, with the shuttle block by having a head 90 thereof fitted upon the spindle 79, stops 91 and 92 being provided on the shuttle block for engagement alternately with said limiting member as the 75 shuttle block reaches the limits respectively of its rocking or pivotal movement on the spindle of the orbital arm. Various means may be employed for closing the clamping jaws of the shuttle when it reaches the initial 80 position, in order to cut the tie loose and engage the free end of the tie wire for a subsequent operation, the means illustrated in the drawings being a rocker frame 93, fulcrumed as at 94 and actuated by a cam 95 on the exterior twister shaft, said rocker frame having an arm 96 which occupies a position above the tail 85 of the shuttle clamp as the latter reaches the prescribed position. The downward stroke of the arm 96 upon the tail 95 of the clamp serves to produce the desired operation of the clamp and cutter.

The operation of the machine may be described as divided into periods of four units each. During two of these units the carrier is moved forward and positioned for the next twisting operation, during the succeeding single period the shuttle moves from the position of grasping or engaging the extremity of the tie wire to the position of delivery of said tie wire to the jaws of the twister head, and during the final unit of operation the twister is rotated and the shuttle is returned to its initial position. The periodic operation of the twister is 100 effected as hereinbefore described, by means of the oscillatory rack 66 and cooperating parts, controlled by the tappet arm 69 and the tappets 70 and 71, and in order that a proper operation as above described of the 105 shuttle may be effected, motion being communicated thereto from the continuously rotating crank disk 87, it is necessary that during two units of the period of operation of the machine, said crank disk shall move 110 without affecting the rack 86' which communicates motion to the pinion 78. To this end a break-joint pitman 97 is employed to connect the wrist pin 98 of the crank disk with the rack 86', said pitman consisting of 115 the pivotally connected members 99 and 100 which are adapted as shown in Fig. 2, to fold or assume positions out of alinement with each other while the wrist pin is traveling through that half of its course which 120 125 130

is represented on the drawings, Fig. 1, as *a*—*b*—*c*, and to be extended or brought into substantial alinement and thereby communicate motion to the rack during the movement of said wrist pin through the path represented by *c*—*d*—*a* in said figure. The member 100 is shown extended beyond its pivotal connection with the member 99 to form a limiting arm 101, adapted to be brought into contact with a stop pin 102 on the member 99 when the said members are extended, and said limiting arm also has a function as a means for maintaining the said members in their operative positions during the movement of the wrist pin from *d* to *a*, while the shuttle is returning for a new engagement with the tie wire, the breaking of the joint or disalinement of said members being effected at the point *a* by reason of the increased resistance to the movement of the rack, due to the fact that the shuttle has reached the limit of its movement effected by the rack and pinion.

What is claimed is:

1. A carrier having sack holders, means for intermittently moving the same, a twister having wire-engaging means, an oscillatory shuttle for engaging the wire and traversing a path around a sack neck in the holder presented by the carrier, and mechanism for intermittently actuating the shuttle during the interval of rest of the carrier.

2. A carrier having sack holders, means for intermittently moving the same, a twister having wire-engaging means, an oscillatory shuttle for engaging the wire and traversing a path around a sack neck in the holder presented by the carrier, and mechanism for intermittently actuating the shuttle during the interval of rest of the carrier, said shuttle having an orbital arm and a reversible body carried thereby and provided with wire-engaging means.

3. A carrier having sack holders, means for intermittently moving the same, a twister having wire-engaging means, an oscillatory shuttle for engaging the wire and traversing a path around a sack neck in the holder presented by the carrier, and mechanism for intermittently actuating the shuttle during the interval of rest of the carrier, said shuttle having an orbital arm, a body reversibly mounted upon said arm, and wire cutting and engaging means carried by said body.

4. A carrier having sack holders, means for intermittently moving the same, a twister having wire-engaging means, an oscillatory shuttle for engaging the wire and traversing a path around a sack neck in the holder presented by the carrier, and mechanism for intermittently actuating the shuttle during the interval of rest of the carrier, said shuttle having an orbital arm, a clamp-carrying body reversibly mounted upon the arm, and

means for limiting the movement of the body relative to the arm.

5. A carrier having sack holders, means for intermittently moving the same, a twister having wire-engaging means, an oscillatory shuttle for engaging the wire and traversing a path around a sack neck in the holder presented by the carrier, and mechanism for intermittently actuating the shuttle during the interval of rest of the carrier, said shuttle having an orbital arm, a block reversibly mounted upon said arm and carrying a wire-engaging clamp, and means for limiting the movement of said block relative to the arm, the same including a follower pivotally connected with the block, and stops on the latter for engagement with said follower.

6. A carrier having sack holders, means for intermittently moving the same, a twister having wire-engaging means, an oscillatory shuttle for engaging the wire and traversing a path around a sack neck in the holder presented by the carrier, and mechanism for intermittently actuating the shuttle during the interval of rest of the carrier, said twister having a wire-engaging head consisting of relatively rotatable disks provided with registrable notches forming jaws for engaging the wire.

7. A carrier having sack holders, means for intermittently moving the same, a twister having wire-engaging means, an oscillatory shuttle for engaging the wire and traversing a path around a sack neck in the holder presented by the carrier, and mechanism for intermittently actuating the shuttle during the interval of rest of the carrier, said twister having a head consisting of relatively revolute disks provided with wire-engaging notches, means for imparting rotary motion to one of said disks, and means for yieldingly resisting the rotary motion of the other disk.

8. A carrier having sack holders, means for intermittently moving the same, a twister having wire-engaging means, an oscillatory shuttle for engaging the wire and traversing a path around a sack neck in the holder presented by the carrier, and mechanism for intermittently actuating the shuttle during the interval of rest of the carrier, said twister having a head consisting of relatively revolute disks provided with wire-engaging notches, telescoping tubular shafts respectively carried by said disks and provided with registering lateral openings forming a wire guide, means for applying rotary motion to one of said disks, and means for yieldingly resisting the rotation of the other disk.

9. A bag-tying machine having a twister, a shuttle for positioning the tie wire with reference to the twister, and means for operating said elements, in combination with

a rotary carrier provided with bag holders, and means for imparting an intermittent movement to said carrier to successively present the holders to the twister, each holder having relatively movable jaws, and a jaw-operating element for alternately opening and closing the same.

In testimony that I claim the foregoing as my own, I have hereto affixed my signature in the presence of two witnesses.

SETH A. WELLMAN.
